UNITED STATES PATENT OFFICE.

WILLIAM M. SAUNDERS, OF WATERBURY, CONNECTICUT, ASSIGNOR TO THE HOGE MANUFACTURING COMPANY, OF NEW YORK, N. Y., A CORPORATION OF NEW YORK.

PENCIL.

1,328,300.

Specification of Letters Patent. Patented Jan. 20, 1920.

Application filed October 16, 1919. Serial No. 331,019.

To all whom it may concern:

Be it known that I, WILLIAM M. SAUNDERS, a citizen of the United States, residing at Waterbury, county of New Haven, State 5 of Connecticut, have invented a certain new and useful Improvement in Pencils, of which the following is a full, clear, and exact description.

My invention relates to improvements in 10 pencils and has for its object to produce a lead propelling pencil which is simple in construction and yet efficient in operation. It further has for its object a provide a pencil having a lead propelling means in 15 which the follower when it reaches the end of its throw will not injure other parts or be injured itself by a further movement of revolution of the actuating means. It further has for its object to provide a pencil 20 whose follower is not liable to bind on the barrel. It further has for its object to provide a pencil having a magazine member forming a part of the propelling mechanism which is held permanently in position without 25 having the holding means or its location apparent from the outside. It further has for its object to provide a yielding lead holder beyond the tip of the lead carrier.

One feature of my invention is the helical 30 spring and means for holding it against rotation under normal conditions. Another feature is the construction whereby excessive movement of the follower unlocks the spring so that it is free to rotate. Another 35 feature is in having the spring spaced from the side wall of the barrel and adjacent to the carrier-tube so that the follower is not liable to bind on the barrel. Another feature is the means for frictionally holding 40 the carrier and rotatable connected parts fixed in place within the barrel by invisible means.

Another feature is the spiral spring tip for the lead carrier.

45 The following is a description of an embodiment of my invention, reference being had to the accompanying drawings, in which,

Figure 1 shows a longitudinal section of a 50 pencil embodying my invention;

Fig. 2 shows on an enlarged scale a portion of the same with the upper end of the spring retracted from its ratchet tooth by a continued rotary movement of the follower-

tube after the follower has reached its upper 55 position;

Fig. 3 shows on an enlarged scale the yielding lead guiding means of Fig. 1.

Fig. 4 shows a side and lower end view of the lead and follower carrier tube complete; 60

Fig. 5 shows end and side views of the anchorage member or upper bushing;

Fig. 6 shows in section and plan view a retaining ring;

Fig. 7 shows in side and end elevation the 65 tubular portion of the revolving plug;

Fig. 8 shows in end and side elevation the cap of the plug; and

Fig. 9 shows in plan and side elevation a second stationary anchorage member. 70

Referring more particularly to the drawings, 1 is a pencil barrel tapered at its upper or point end (Fig. 1) and containing, adjacent to said tapered end, a tightly fitting bushing 2 through which projects 75 the end of a revoluble tubular carrier 3, which end is thereby held in line with the opening in the point or tapered end through which the lead 4 is introduced and expelled.

Above the upper extremity of the carrier 3 80 is loosely held a double cone-shaped, easily yielding, helical spring 5 so as to provide a yielding lead-guiding means, the central helix of which grips the lead slightly so as to prevent its freely slipping out of the 85 pencil.

The upper conical end of this spring forms a conical guide for the end of the lead as it is inserted through the opening in the small end of the tapered portion. 7 is a stationary ring shaped anchorage 90 tightly fitting the interior of the bore of the barrel 1 so that when forced therein it will be held in position by friction, in the same manner as is the portion 2. Between the anchorages 2 and 7 is a helical spring 8 95 whose respective ends bear with a slight degree of pressure against the opposing faces of the members 2 and 7, which are provided respectively with recesses 9 and 10 having oppositely facing abrupt shoulders 100 forming ratchet teeth or abutments adapted to be respectively engaged by the pawl-like ends of the wire forming the spring to prevent the spring from turning when both anchorages members are engaged thereby. 105

The follower-carrier 3 passes through the spring 8. The body portion 11 of the carrier contains a follower 12 having its lower

end 13 formed with a lateral projection, which lies between two adjacent helices of the spring 8, the carrier-tube being provided with an elongated slot 14 through which 5 this projection 13 protrudes. The upper end of the tube 3 extends through the member 2 so as to be journaled therein and to be held thereby in alignment with the axis of the barrel 1. The spring 8 is spaced away from 10 the interior of the casing 1 and is in close proximity to the exterior of the body portion 11 of the follower-tube 3, preferably as close as it can be and yet permit the carrier 3 to turn easily therein. With this construction 15 the follower extension 13 can be made so short as to clear the interior of the barrel 1 by a considerable amount. Connected to the lower end of the follower-carrier 3, preferably by solder, is a head 16 20 having brazed thereto a shell 17, these two parts constituting a plug of such size that while closely fitting the interior of the barrel 1 it is free to rotate therein. The shell 17 extends beyond the barrel 1 and is provided 25 with a cap 18 which fits thereon, the shell being provided with a slit 19, in which an internal projection 20 upon the cap fits so as to prevent relative rotary movement between the cap and the plug. This plug 30 being hollow and the cap being removable, a receptacle is thus provided for storing extra leads. The plug is provided with an annular groove 21, formed in the shell 17, in which fits a ring 22, the ring 22 being of 35 such size as to turn easily in the groove 21 and yet to so fit the bore of the barrel 1 as to be firmly held therein by friction so as to be practically unremovable therefrom. This ring is cut at one side so that it can be 40 passed over the end of the tubular member 17 into the groove 21 before the plug is inserted within the barrel. After the ring 22 has been positioned in the groove 21 the plug and ring are forced into the barrel 1 45 by a suitable tool in assembling the pencil.

In assembling the pencil as a whole, the spring 5 is first dropped in place, the bushing 2 is then forced into position in the barrel where it is held by friction against the 50 barrel. The other parts to be contained within the barrel are then assembled outside the barrel in the relations shown in Fig. 1 and all inserted into the barrel at one operation, the upper end of the carrier-tube 3 passing through the bushing 2 so as 55 to be aligned thereby and the rings 7 and 22 being forced to their proper positions relative to one another and to the bushing 2, where they are held by friction. The preliminary and final assembling are thus 60 simple matters.

In the operation of the pencil turning the cap 18 turns the follower-tube and follower. The end 13 of the follower, traveling between adjacent helices of the spring 8, causes

the follower to move in one direction or the other and to propel the lead outwardly or to permit the lead to be shoved in. In order that the follower after it has reached the limit of its movement in either direction 70 may not be injured itself or injure other parts of the pencil by the continued movement of the positively connected cap 18, the spring 8, while stiff, is made sufficiently resilient so that it can be compressed somewhat by the follower when at its limit of axial movement without injury to any part. Thus, while the follower is approaching its 75 uppermost position, the spring is held from turning by the pawl-like engagement of its upper end with the recess 9. If, when the follower has reached its uppermost position, there is a further turning movement in the same direction the spring is compressed by the follower so that its pawl-like upper end 80 is withdrawn from the recess 9, as in Fig. 2, whereupon the spring, as a whole, is free to turn with the carrier 3 and cap 18 and does turn without injury. In a similar way, when the follower reaches its lowermost 85 position, i. e., engages the bushing 7, it acts upon the lower end of the spring to withdraw it from the recess 10, whereupon the spring is free to turn without injury if the cap 18 is further turned in the same direction. When the rotary movement of the follower is reversed after reaching its lowermost position, the projection 13 passes above the lower end of the spring, which has in the meantime entered the recess 10 so as 90 to lie within the flat surface of the bushing 7. This simple means of securing in position the spring, without binding lateral engagement with any element of the pencil, constitutes an important feature of my invention and provides a positive and durable 95 safety feature.

As will be evident to those skilled in the art, my invention permits of various modifications without departing from the spirit 100 thereof or the scope of the appended claims.

What I claim is:

1. In a pencil, the combination of a barrel, a follower-carrier rotatably mounted therein, a follower for said carrier, a helical spring surrounding said carrier and rotatable relatively to said carrier and barrel, said follower engaging said spring, and fixed means within said barrel normally engaged by the ends of said spring so as 115 to hold said spring from turning, said ends being movable by said follower axially of said pencil relatively to said fixed means so as to disengage the same.

2. In a pencil, the combination of a barrel, a follower-carrier therein, anchorage members fixed within said barrel and spaced apart along said carrier, a helical spring surrounding said carrier between said anchorage members and rotatable relatively 120 to 130

to said carrier and barrel, said members having abutment faces normally engaging the ends of said spring and holding it from turning, means connected with said carrier 5 for revolving the same within said barrel, and a follower within said carrier having a portion engaging said helical spring, the ends of said spring being movable by said follower axially of said pencil relatively to 10 said abutment faces so as to disengage the same.

3. In a pencil, the combination of a barrel, a follower-carrier therein, anchorage members fitting closely within said barrel 15 and spaced apart along said carrier, said members having recesses providing stop faces, a spring surrounding said carrier and having its ends normally engaging said stop faces, and means connected with said carrier 20 for revolving the same within said barrel, said spring being spaced away from said barrel and closely adjacent to said carrier.

4. In a pencil, the combination of a barrel having a tapered end, a follower-carrier therein, anchorage members fixed within said barrel and spaced apart along said carrier, a helical spring surrounding said carrier between said anchorage members and rotatable relatively to said carrier and 30 barrel, said members having abutment faces normally engaged by the ends of said spring so as to hold it from turning, means connected with said carrier for revolving the carrier within said barrel, and a follower 35 within said carrier having a portion engaging said helical spring, the anchorage mem-

ber nearest to the tapered end of said barrel acting to aline said carrier, the ends of said spring being movable by said follower axially of said pencil relatively to said abut- 40 ment faces so as to disengage the same.

5. In a pencil, the combination of a barrel having a tapered end, a helical surface within said barrel, a slotted follower-carrier tube located axially within said barrel, a 45 follower within said tube and having a projection engaging said helical surface, a rotatable plug secured to said tube and having an annular recess, and a ring within said recess and in fixed frictional engagement 50 with the interior of said barrel remote from said tapered end, the inner surface of said barrel engaged by said ring being cylindrical, and means for centering within said barrel the end of said carrier tube remote 55 from said plug.

6. In a pencil, the combination of a barrel having a tapered end, a helical surface within said barrel, a slotted follower-carrier tube located axially within said barrel, a 60 follower within said tube having a projection engaging said helical surface, a rotatable plug secured to said tube, means for holding said plug against longitudinal movement in said barrel, means for centering within said barrel the end of said carrier-tube remote from said plug, and a 65 spring member adjacent to said remote end for holding and guiding the lead, said spring member being engaged by said follower-carrier and held in position thereby. 70
